US00D949969S

(12) **United States Design Patent** (10) **Patent No.:** **US D949,969 S**
(45) **Date of Patent:** **** Apr. 26, 2022**

(54) **BINDER MECHANISM**

(71) Applicant: **CCL Label, Inc.**, Framingham, MA (US)

(72) Inventor: **Manuel Amaya**, San Diego, CA (US)

(73) Assignee: **CCL LABEL, INC.**, Framingham, MA (US)

(**) Term: **15 Years**

(21) Appl. No.: **29/713,848**

(22) Filed: **Nov. 19, 2019**

(51) LOC (13) Cl. **19-04**

(52) U.S. Cl.

USPC **D19/32**

CLAIM

The ornamental design for binder mechanism, as shown and described.

DESCRIPTION

FIG. 1 is a front view of a binder mechanism showing my new design;

FIG. 2 is a front view thereof;

FIG. 3 is a rear view thereof;

FIG. 4 is a first side view thereof;

FIG. 5 is a second view thereof;

FIG. 6 is a top view thereof; and,

FIG. 7 is a bottom view thereof.

The broken lines in the figures are included for the purpose of illustrating portions of a binder mechanism and form no part of the claimed design.

1 Claim, 4 Drawing Sheets
